[57] CLAIM

[22] Filed: Sep. 22, 1977

The ornamental design for a combined watch face and
hands, substantially as shown.

[51] Int. Cl. ..... D10—07

DESCRIPTION

[52] U.S. Cl. D10/124

[58] Field of Search D10/122-126,
D10/21-27, 1; 58/126 R, 126 A, 127 R, 88 G,
88 RThe FIGURE is a front elevational view of a combined
watch face and hands showing my new design; the face
and hands are conventionally of no appreciable thick-
ness while the rear is flat, plain and unornamented.U.S. Patent
